UNITED STATES PATENT OFFICE.

MARY E. McCONNELL, OF SEATTLE, WASHINGTON.

SHIRT-WAIST HOLDER AND SKIRT-SUPPORTER.

No. 854,301.

Specification of Letters Patent.

Patented May 21, 1907.

Application filed June 2, 1906. Serial No. 319,871.

To all whom it may concern:

Be it known that I, MARY E. McCONNELL, a citizen of the United States, residing at Seattle, in the county of King and State of Washington, have invented certain new and useful Improvements in Shirt-Waist Holders and Skirt-Supporters, of which the following is a specification, reference being had therein to the accompanying drawings, in which—

10 Figure 1 is a perspective view of an embodiment of my invention looking from the front; Fig. 2, a similar view looking from the opposite side; and Fig. 3, an end view of the same.

15 The object of this invention is the provision of a simple, efficient and inexpensively constructed device whereby a woman's skirt may be conveniently attached to or disconnected from her shirt-waist or basque and 20 which is capable of supporting the same with but little liability of its becoming torn.

With these ends in view the invention consists in the novel construction, adaptation and combination of parts as will be herein- 25 after described and claimed.

In the said drawings, the reference letter *a* designates the body of the device which is formed of a metallic plate provided in proximity of its ends and lower edge with pairs of 30 apertures *b*. Secured at the rear of the body, and at one of its ends by marginal ears *c* and *d* is a wire *e* which is bent to provide a tongue *f* extending lengthwise of the body and terminating in a point *g* adapted to be caught by a hooked ear *h* thereof. This wire is employed 35 for attaching to a shirt-waist, as by the ordinary type of safety pin, and desirably by threading it through a number of folds of the garment to afford an extended support. The 40 skirt is hung from said body by being en-

gaged at the waist-band thereof with the rearwardly and upwardly protruding double pronged wire-hooks *i*. These hooks have their central portions *k* secured to the body at the front by turning the ears *l* of the latter 45 thereabout and the hook ends are then bent and passed through said apertures and maintained in operative position by the ears *m* folded over such bends. The hooks being disposed near the ends of the body will 50 obviously distribute the weight which is borne and be less likely to tear the suspended garment than if supported at a single point.

The device is capable of being quickly attached to or detached from the garments and 55 is extremely valuable for the purposes indicated.

Having described my invention, what I claim as new and desire to secure by Letters-Patent, is—

A device of the class described comprising a plate having spaced transverse apertures and with a plurality of tongues extending from its side edges and arranged in pairs, the tongues at one side bent into sockets and the tongues at 65 the other side bent into keeper devices, a resilient pin supported at one end in one of said sockets and adapted to be housed at the free end in another of said sockets, and U-shaped pins supported at their bends in the remaining 70 sockets and extending through said apertures and maintained in position in the rear of said keeper devices.

In testimony whereof I affix my signature in presence of two witnesses.

MARY E. McCONNELL.
